(57) **CLAIM**

The ornamental design for a digital camera docking station, as shown and described.

DESCRIPTION

FIG. 1 is a front isometric view of a first embodiment of a digital camera docking station;

FIG. 2 is a rear isometric view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a front isometric view of a second embodiment of a digital camera docking station;

FIG. 10 is a rear isometric view thereof;

FIG. 11 is a top plan view thereof, the bottom plan view being shown in FIG. 4;

FIG. 12 is a front elevational view thereof;

FIG. 13 is a rear elevational view thereof;

FIG. 14 is a left side elevational view thereof; and,

FIG. 15 is a right side elevational view thereof.

The portions of the digital camera docking station in broken lines are shown for illustrative purposes only and form no part of the claimed design.
